UNITED STATES PATENT OFFICE.

ERASTUS E. WINKLEY, OF LYNN, MASSACHUSETTS, ASSIGNOR OF ONE-HALF
TO BENJAMIN PHILLIPS, OF SAME PLACE.

SOLE-LAYING MACHINE.

SPECIFICATION forming part of Letters Patent No. 553,949, dated February 4, 1896.

Application filed October 4, 1895. Serial No. 564,587. (No model.)

To all whom it may concern:

Be it known that I, ERASTUS E. WINKLEY, a citizen of the United States, and a resident of Lynn, in the county of Essex and Commonwealth of Massachusetts, have invented a new and useful Improvement in Sole-Laying Machines, of which the following, taken in connection with the accompanying drawings, is a specification.

10 The present invention relates to improvements in machines of the above class; and it consists of the combination, with a rotary carrier carrying a series of pressing-forms and their associated shoe-supporting jacks, of certain novel devices and combinations of devices, as hereinafter more specifically set forth and claimed.

15 The object of the present invention is to increase the efficiency and rapidity of operation of this class of machines, and to eliminate, as far as practical, such devices as have heretofore required the direct manual control of the operator.

20 The present invention is illustrated in the accompanying drawings, in which—

Figure 1 is a side view of a sole-laying machine embodying the present invention. Figs. 2 and 3 are detached views of the jack, taken, respectively, in plan and side elevation. Fig. 30 4 is a front view of a machine embodying the present invention.

Similar letters and figures of reference refer to similar parts throughout the several views.

35 In the drawings, A represents a frame suitable to support the working parts of the machine.

40 B represents a rotary carrier conveniently in the form of a spider-frame, which, as shown, is mounted upon a shaft b supported by the frame A and conveniently actuated by the following mechanism: The shaft b is projected rigidly from the frame A, forming a journal for the hub b' of the spider-frame B. The 45 hub b' of the spider-frame B projects inwardly beyond the spider-frame and carries a gear b² which is rigidly mounted thereon and rotates therewith. The gear b² meshes with a gear b³ on the shaft b⁴, which is free to rotate in 50 suitable bearings in the frame A, and to which power is applied as hereinafter described.

D D D, &c., represent the pressing-forms, the construction of which I do not consider it necessary to describe herein in detail, as the same forms no part of the present invention. It is sufficient to say that the forms D D D, &c., may be of any suitable construction for the purposes hereinafter described.

E E E, &c., represent a series of shoe-supporting jacks, which also may be of any suitable form. As shown in the drawings, each of the jacks E comprises a heel-support e and a toe-rest e', supported by a suitable bed-plate e². For convenience of adjustment the heel-support e is mounted upon a block or plate e³ and the toe-rest e' upon a block or plate e⁴. The plates e³ and e⁴ are fitted to the parallel gibs or ways e⁵ upon the bed-plate e², along which they are free to slide. From one side of the plate e³ is longitudinally projected a rack e⁶, and from the opposite side of the plate e⁴ is similarly projected a rack e⁷. The racks e⁶ and e⁷ engage opposite sides of an idle-gear e⁸ journaled upon the bed-plate e², the arrangement being such that an inward movement of the heel-support e produces an outward movement of the same extent of the toe-rest e', making the center of the jack a position-point for any length of last.

45 In practice I find it convenient to provide a spring-pressed pawl e⁹ pivotally mounted upon the bed-plate e², and arranged to engage with a series of notches e¹⁰ on the plate e⁴ and lock the toe and heel supports in the desired position. The pawl e⁹ is in a convenient position to be released by the operator when it is desired to adjust the jack.

50 Each of the jacks E E E, &c., is associated with a form D, and is in operative relation thereto when a shoe supported by the jack E is held thereby with its sole in position to be acted upon by the form.

55 Each of the jacks E E E, &c., is capable of movement out of operative relation with its associated form D, whereby it is presented to the operator in position for the removal of a shoe therefrom, and of a reverse movement, whereby it is again brought into operative relation with said form.

60 I find it convenient to secure the movement of the jacks, as above referred to, by the following mechanism, to which however I do not

consider the present invention limited, as many variations may be made therein by one of average skill in the art without involving any departure from the present invention.

5 The bed-plate e^2 of each of the jacks E is fitted to a lateral slideway b^5 in the bed b^6 on the spider-frame B, along which it is free to reciprocate. From the bed-plate e^2 is forwardly projected a downwardly-bent finger 10 e^{11} which engages a segmental groove e^{12} formed upon the periphery of the vertical block e^{13} which is mounted upon and reciprocates with the shaft e^{14} .

The above-described arrangement is such 15 that during a portion of the rotation of the spider-frame B the finger e^{11} is in engagement with the segmental groove e^{12} and the bed-plate e^2 is reciprocated along the way b^5 by the reciprocation of the shaft e^{14} , and as the spider-frame B is further rotated (the block e^{13} having no motion of rotation) the finger e^{11} disengages itself from the groove e^{12} , and, during 20 the rest of the rotation of the spider-frame B, the position of the bed-plate e^2 is not changed 25 by any reciprocation of the shaft e^{14} .

The shaft e^{14} extends through the journal b of the spider-frame B which is centrally chambered to receive the same, forming a bearing and support therefor in which the 30 shaft e^{14} is free to reciprocate longitudinally, being guided and held in position thereby. To the shaft e^{14} by the pivotal slotted connection σ^2 is connected a swinging lever e^{15} fulcrumed at e^{16} upon the frame A, and which 35 intermediately carries a cam-roll e^{17} , which works in a cam-path e^{18} upon the cam-wheel e^{19} which is mounted upon and rotates with the shaft b^4 . The throw of cam-path e^{18} is such that by means of the lever e^{15} it imparts to the 40 shaft e^{14} a motion of longitudinal reciprocation which moves the plate e^2 and its jack E along the lateral ways b^5 from a position under its form D, substantially as shown, to a position wholly or partially removed from beneath the form convenient for the removal or 45 adjustment of a shoe thereon, and thereafter returns the plate e^2 and its jack E to their original position. The cam e^{18} is so formed and timed with reference to the mechanism 50 for rotating the spider-frame B and the mechanism for bringing the forms D D, &c., into a position of clearance that the lateral movement of each jack, as above described, occurs while its form is in a position of clearance, 55 and preferably as the jack approaches and just after it passes a vertical position, at the highest point of its rotation.

In the above arrangement the outward movement of the jack occurs as it approaches 60 a vertical position as above described, and its inward movement as it leaves such position, and by such arrangement the jack, when presented to the operator, is in a most convenient position for the removal of the finished shoe and adjustment of shoe to be operated upon by the machine.

In practice I find it convenient to provide

for an adjustment of the block e^{13} along the rod e^{14} to insure the return of the jack E to a proper position under the form D. To insure 70 such result the block e^{13} is mounted upon a collar or sleeve 2, which is keyed to the shaft e^{14} . The block e^{13} is free to slide along the sleeve 2, but is held from rotation about the same by a feather 3, which engages a feather-way in the block e^{13} . From the shaft e^{14} is projected a short arm 4, which supports in suitable bearings a rod 5, the inner portion of which is threaded and engages a threaded bearing in the block e^{13} . An operating-handle 6 may be conveniently provided, by means of which the rod 5 may be rotated and the block e^{13} moved in either direction along the sleeve 2. It is desirable to note in this connection that the arrangement of the groove 85 e^{12} is such that each of the fingers e^{11} engages the same in turn and remains in engagement therewith while its jack is reciprocated by the cam e^{18} , and it is to be further stated that, as shown in the drawings, each of the 90 fingers e^{11} engages the groove e^{12} after the form has been returned to such position, each finger e^{11} remaining in engagement with the groove e^{12} while its form is clear of its jack, an arrangement which insures the finger e^{11} 95 being in position to engage the groove e^{12} as the spider-frame B is rotated. As before stated, the fingers e^{11} engage the groove e^{12} in turn as the spider B rotates, and it may be unnecessary to add that only one of the fingers e^{11} is in engagement with the groove e^{12} 100 at any time.

As already stated, the forms D D, &c., have a vertical motion from a position of pressure to a position of clearance, and vice versa. I 105 would say in this connection that by a "position of pressure," as the term is herein used, I mean that position of the form with reference to its jack which the form assumes when the sole of a shoe, mounted upon the jack, is 110 being compressed in the operation of laying the same, and by a "position of clearance" is meant that position which the form assumes with reference to its jack to allow the jack to be moved with a shoe thereon from beneath 115 the jack to a position convenient for the removal of the shoe therefrom.

To impart the movement above defined to the forms D D, &c., I have adopted the following mechanism, but I wish to say that, in 120 the specific form described, it constitutes no essential feature of the present invention, and the same result may be secured in other ways without any departure therefrom.

Each of the forms D D, &c., is secured to 125 a vertical movable form-carrier d , which, as shown, is held in position by the guides d' d' d' (only two shown) on the arms of the spider-frame B, along which the carrier d is free to reciprocate radially to the spider-frame. To the carrier d are secured a series of springs d^2 d^2 d^2 , &c., (two shown, 130 which are secured also to the spider-frame B, and which act to approximate the carrier d

to the hub b , and hence to force the form D down upon its jack E or a shoe placed thereon. From opposite sides of each of the carriers D project the cam-rolls $d^3 d^3$, which are arranged 5 to engage the camways $d^4 d^4$, one of which is supported by the frame A or a suitable bracket thereon, and the other by the laterally and downwardly extending arm a , rigidly projected from the frame A. The above-described arrangement is such that as the spider-frame B is rotated the rolls $d^3 d^3$ enter the camways $d^4 d^4$ when their form D is in a position of pressure, and traveling up the camways $d^4 d^4$ raise the form D to a position of 15 clearance. As the rotation of the spider-frame B continues, the rolls $d^3 d^3$ travel down the camways $d^4 d^4$, allowing the form D to be brought in contact with a shoe on the jack and finally disengage themselves from the 20 camways $d^4 d^4$, leaving the form D in a position of pressure during the rest of the rotation of the spider-frame. I would say in this connection that I have connected each of the forms D D, &c., with its carrier d by a 25 pivotal connection d^5 , which is located near the center of the form, and allows the form to tip longitudinally to adjust itself to the work. The camways $d^4 d^4$ are so formed and arranged with reference to the cam e^{18} and the 30 mechanism for rotating the spider B that the devices controlled thereby perform their function in due relation order.

In connection with my present invention I have provided a stop mechanism whereby the 35 rotation of the spider and lateral movement of each jack is stopped automatically when each jack is in a convenient position for the removal of a shoe therefrom. A convenient form of such mechanism is described as follows:

7 represents a transverse shaft, free to rotate in suitable bearings in the frame A, and to which power may be applied by a belt on the pulley 8 or other suitable means. The 45 shaft 7 carries a worm 9, which engages the worm-gear 10 on the shaft b^4 . On the hub of the gear 10 are formed the laterally-projected teeth 11, which are adapted to engage with the teeth 12 on a sleeve 14. The sleeve 14 is 50 splined to the shaft b^4 , being arranged to rotate therewith and free to slide along the same. A spring 15, preferably coiled around the shaft b^4 and bearing against a suitable collar 16 thereon, normally acts to keep the 55 teeth 11 and 12 in engagement, so that the shaft b^4 rotates with the gear 10. From the sleeve 14 is laterally projected a pin 18, which, as the sleeve 14 rotates, engages the wedge 17 and moves back the sleeve 14 against the tension of the spring 15, disengaging the teeth 11 and 12 and stopping the rotation of the 60 shaft b^4 .

As shown in the drawings, the diameter of gear b^2 is four times the diameter of gear b^3 , 65 so that a single pin 18, upon the sleeve 14, stops the spider B at every quarter-turn, which, in

a four-jack machine, as shown, gives the desired result, the pin 18 being so placed as to stop the rotation of the spider B as each jack is presented to the operator.

70

The wedge 17 is mounted upon and rotates with a rod 19, which is mounted in suitable bearings in the frame A, in which it is free to rotate. The rod 19 carries a crank-treadle 20, by means of which it may be rotated. A 75 rotation of the rod 19 turns the wedge 17 out of the way of the pin 18, and allows the spring 15 to advance the sleeve 14 until the teeth 11 and 12 engage.

A suitably-placed spring (not shown in the 80 drawings) may be conveniently provided to raise the treadle 20 and bring the wedge 17 in the path of the pin 18.

The operation of the present invention is described as follows: When the machine is 85 at rest, one of the jacks E is presented to the operator, being wholly or partially out from beneath its form D, which is in a position of clearance. The finger e^{11} associated with the exposed jack is engaged by the segmental 90 groove 12, and the rolls $d^3 d^3$ of its form-carrier d are engaged by the camways $d^4 d^4$. All the other jacks are beneath their respective forms, which are in a position of pressure. The operator places a shoe upon the jack 95 which is presented to him and starts the rotation of the spider-frame B by depressing the treadle 20. As the rotation of the spider-frame B commences, the shaft e^{14} moves inward, carrying the jack E under its form D, 100 which has been held for that purpose in a position of clearance, the rolls $d^3 d^3$ having traveled over a circular portion of the camways $d^4 d^4$. (See Fig. 4.) When the jack E is in position under its form D the rolls $d^3 d^3$ 105 have traveled over the circular portion of the ways $d^4 d^4$ and move inward along the same, allowing the springs $d^2 d^2 d^2 d^2$ to force the form D downward into a position of pressure. When the form D is in a position of pressure, 110 the rolls $d^3 d^3$ disengage themselves from the camways $d^4 d^4$ and the finger e^{11} from the groove e^{12} , and the jack E is left under the pressure of its form for the rest of the rotation of spider B. As the rotation of spider B continues, 115 the finger e^{11} on the next jack E enters the groove e^{12} and the roll $d^3 d^3$ on its form-carrier d enters the camways $d^4 d^4$. As the rolls $d^3 d^3$ enter the ways $d^4 d^4$ they are forced outward against the tension of the springs $d^2 d^2$ 120 $d^2 d^2$, bringing the form D into a position of clearance, when the shaft e^{14} is again advanced, moving the last E out from beneath the form D and presenting it to the operator in a convenient position for removal or adjustment of a shoe, when the rotation of spider-frame B and the lateral movement of last are stopped by the pin 18 coming in contact with the wedge 17, as hereinbefore explained. 125

The operation above described may be indefinitely repeated, the operator removing 130

the finished work and adjusting new work as each jack is presented to him and depressing the treadle to start the machine.

I would say that I am aware of the state of the art as shown in Letters Patent to Coy and Paul, September 9, 1890, No. 436,034, also to Coy, January 10, 1888, No. 376,406, and Coller, June 13, 1876, No. 178,598, all in the class of sole-machines, and I claim nothing shown therein. I am not, however, aware that it has heretofore been proposed to construct a sole-laying machine embodying a rotary carrier and movable jacks and forms mounted thereon in which the three essential movements of pressure, clearance, and presentation of the jacks to the operator have been accomplished automatically.

I therefore claim as novel and desire to secure by Letters Patent—

- 20 1. In an organized sole-laying machine the combination of a rotary carrier, a series of pressing-forms mounted upon the carrier, a series of shoe-supporting jacks, associated respectively with the pressing-forms, mounted upon the carrier and movable transversely to the plane of its rotation, and connected mechanisms, operating automatically to produce compression and clearance between each form and its associating jack, and to rotate the carrier and actuate the jacks, whereby one jack is presented to the operator in convenient position for the removal of a shoe therefrom, while the other jacks remain under pressure, substantially as described.
- 25 2. In an organized sole-laying machine the combination of a rotary carrier, a series of pressing-forms mounted upon the carrier, a series of shoe-supporting jacks, associated respectively with the pressing-forms, mounted
- 30 3. In an organized sole-laying machine the combination of a rotary carrier, a series of pressing-forms mounted upon the carrier, a series of shoe-supporting jacks, associated respectively with the pressing-forms, mounted
- 35 4. In an organized sole-laying machine the combination of a rotary carrier, a series of pressing-forms mounted upon the carrier, a series of shoe-supporting jacks, associated respectively with the pressing-forms, mounted
- 40 in suitable transverse guideways upon the carrier, along which they are free to recipro-

cate transversely to the plane of the rotation of the carrier, said guideways, and connected mechanisms operating automatically to produce compression and clearance between each 45 form and its associated jack, and to rotate the carrier and actuate the jacks, whereby one jack is presented to the operator in convenient position for the removal of a shoe therefrom while the other jacks remain under pressure, substantially as described.

3. In a sole-laying machine the combination of a rotary carrier, a series of pressing-forms mounted upon the carrier, a series of shoe-supporting jacks, associated respectively with the pressing-forms, mounted upon the carrier and movable transversely to the plane of its rotation, means for producing compression and clearance between each jack and its associated form, means for rotating the carrier, and mechanism common to all the jacks for independently actuating each jack, substantially as described.

4. In an organized sole-laying machine the combination of a rotary carrier, a series of 65 pressing-forms mounted upon the carrier, a series of jacks mounted upon the carrier each arranged to co-operate with a form and movable out of operative relation thereto, and connected mechanisms, operating automatically to produce compression and clearance between each form and its associated jack, to rotate the carrier, and to actuate the jacks, substantially as described.

Witness my hand, in the presence of two 75 attesting witnesses, this 2d day of October, 1895.

ERASTUS E. WINKLEY.
